UNITED STATES PATENT OFFICE

THEODOR J. BACHOFEN, OF WESTBROOK, MAINE

PROCESS AND APPARATUS FOR MAKING DOUBLE PILE FABRICS

Application filed May 10, 1929. Serial No. 361,879.

This invention relates to a process and apparatus for the manufacture of double pile fabrics, such as transparent velvets, velours and plush, on ordinary high grade box looms.

5 In the art of making double pile fabrics special looms of very expensive type are employed, which cannot be used for weaving ordinary plain fabrics.

One object of the present invention is to 10 provide a simple, practical and comparatively inexpensive device, readily attachable to the common types of box looms, by which they are converted and rendered capable of weaving a double pile fabric, such as real and artificial silk, transparent velvets, velours or pluses and which may also be used for cotton, woolen or worsted mixtures.

20 A further feature is in the provision of means to enable the pile interlacing the double cloth to be conveniently cut during the operation of weaving without any expensive alterations or changes in the loom.

Another purpose is to produce a novel and highly advantageous form of weaving, at 25 one operation, two completely distinct but like sheets or piles of fabric, spaced apart but held one to the other until the pile threads are separated centrally between the fabric sheets thus produced, thereby doubling the ordinary capacity of the loom, while at the same 30 time making the highest quality of goods.

These important objects are accomplished by the novel construction, combination and arrangement of parts hereinafter described 35 and illustrated in the accompanying drawings, constituting a material part of this disclosure, and in which:—

Figure 1 is a longitudinal sectional view 40 of a conventional type of box loom, showing the arrangement of parts constituting the invention, the drawing being largely diagrammatic.

Figure 2 is a diagrammatical plan view 45 showing parts of the elements in Fig. 1 and the disposition of the warp and filler threads during weaving.

Figure 3 is a magnified perspective view 50 showing the arrangement of threads in the woven fabric.

Figure 4 is a further enlarged sectional

view of the two plies or sheets of fabric connected by the pile threads.

Figure 5 is a similar view of one of the plies after the pile threads have been cut and spread apart.

Figure 6 is a partial front elevational view 55 of the loom showing the novel attachments comprising the invention.

Figure 7 is a transverse sectional view taken on line 7—7 of Fig. 6 and drawn to an increased scale.

Figure 8 is a fragmentary plan view of the pile cutting knife, its guide and guard.

Figure 9 is a similar view showing the pile 60 knife and a modified form of guide bar.

As this invention relates solely to the art of weaving and is of interest mainly to persons familiar with the art, only the essential elements of a box loom have been graphically indicated, the showing being largely diagrammatic, both of the product and mechanism by which it is produced.

The particular product is a woven pile fabric, as shown in finished condition in Fig. 5, which is generally indicative of a so-called transparent velvet, velour or plush, having a fine web backing similar to goods known as chiffon, georgette or the like.

In this process of weaving two distinctly separate webs are produced, respectively upper and lower, and generally designated A and B, both being alike and woven in opposed relation at one operation, the webs being spaced apart but connected by interwoven 75 yarns composed of a plurality of fine strands or filaments, which, upon being severed transversely, intermediate the webs, separate and spread out in all directions constitute the pile C.

In greater detail the upper web A is 80 formed by weaving two warp threads e and f in such manner as to pass respectively over and under two of the filler threads m and n, then reversing their relative position to enmesh the next single adjacent filler thread o, again reversing to engage the next pair of filler threads m' and n', thence reversing to 85 pass around the single filled thread o' and continuing in a like manner throughout the length of the web.

The lower web B is formed in a like manner by the two warp threads *g* and *h* which enmesh pairs of filler threads *q*, *p'* and *q'* etc. with intermediate filler threads *r*, *r'*, etc. in the foregoing manner, uniting every third filler thread with adjacent pairs of filler threads.

The pile threads *c* and *d* are interwoven intermediate each pair of warp threads by 10 passing over the filler thread *m* in the upper web A, extending to web B to pass under *q*, over *r*, and under *p'*; then leading upwardly to pass over the filler *n*, under *o*, over *m'* and down under *q'*, over *r'*, and under *p''* to extend upwardly to the web A and recommence a new series of similar weaving ad finitum.

From the foregoing it will be observed that the pile threads are effectively embedded and securely held in both webs A and B in a 20 manner to be held fast therein when the webs are separated by severing the pile threads at a point intermediate the webs, as indicated in Fig. 4, the completed product being shown in Fig. 5.

25. The box loom structure by which this weaving effect is produced is characterized by being provided with a pile yarn beam 15, an upper ground binder thread beam 16 and lower ground beam 17, each having friction brake retarding means, as the weights 18—19—20, differing in degree of force as may be desired.

The threads from the beams are guided by 35 rolls, respectively 21—22—23, to be delivered in planes approximately in registration with the heddles carried by a series of harnesses, six in number and designated respectively 24—25—26—27—28—29, these harnesses being actuated in timed relation, as per pattern, 40 see Fig. 2, by means ordinarily employed, not here shown.

As will be well understood these harnesses move the several threads to form sheds through which the shuttle 30 passes in disposing the weft or filler between the warp threads, at which time the reeds 31 of the lay 32 will be in a rearward position.

The united webs pass under a roll 33 on their way over the breast 34 of the loom, the 50 breast being provided with a roll 35 over which the fabric passes, thence under a smaller roll 36 guiding the fabric around a sand roll 37, to pass over another guide roll 38 and thence to a suitable container.

55. It may be noted that the upper web A is formed by threads *e* and *f*, from the beam 16, the thread *e* being engaged in the harness 24 and the thread *f* in the harness 25. The thread *g* of the lower web is engaged in the harness 26 and the thread *h* in the harness 27, both threads being dispensed from the beam 17.

The pile yarns *c* and *d*, from the beam 15 are actuated by the harnesses 28 and 29 respectively, the harness 28 acting conjunctively

with the first series of four warp harnesses in weaving the web A, and the harness 29 operating with respect to the second series of four warp harnesses in weaving the web B, producing the effect illustrated in Fig. 3, and due to the interweaving of the pile warps, with the webs A and B, so as to extend from one to the other, it will be apparent that greater lengths of the pile yarns are used than of the binder warps.

Referring now more particularly to Figs. 1, 6 and 7, it will be seen that means are provided for cutting the pile yarns midway between the webs A and B, the device consisting of a long knife 40 slidably supported in a holder 41 reduced in width at its ends 41' which are seated on shoes 43 slightly tapered downwardly towards their front edges and provided with overhanging rear edges 44 to receive the holder 41.

Preferably the knife holder 41 is provided with a plurality of guards 42 extending outwardly from the holder above and below the blade to some distance in advance, these guards being in the nature of opening prongs for the fabric and prevent the knife blade from touching either of the webs as may be seen in Fig. 7, although a plain, unguarded holder may be used as shown in Fig. 9.

95. Bolts 45 pass through the reduced ends of the knife holder, as seated on the shoes 43, firmly securing it to the upper side of the breast beam 34 and the arrangement of the bolts is such that the holder and knife therein may be given a slight camber or bowed effect if desired.

100. Secured to the ends of the knife 40 are clips 46 having devices 47 pivoted to their outer ends in which are engaged hook eyes 48—48', the former being secured at the end of a flexible strap or cord 49 trained around a pair of idle pulleys 50 mounted upon a support stand 51 rigidly fixed on the breast beam 34 near one end.

105. A similar but opposed stand 52 at the other end supports idle pulleys 53 around which is trained a strap 49' having at one end the eye 48' and at the other end with a link 54 connecting with the strap 49, the link being in sections between which is interposed a coiled tension spring 55, providing a suitable taut condition of the knife and its connections.

110. An inwardly extending arm 56 of the stand 52 has pivoted to it, at 57, a lever 58 provided, near its free end, with a series of perforations 59 in which may be selectively secured a bolt 60, the head of which is secured to the strap 49' in a manner to communicate motion to the knife when the lever is moved.

115. The outer, movable end of the lever 58 is raised, as at 58', and contactable with its sides are collars 61—61' adjustably spaced on a rod 62 connected at its rear end by hinge 63 to a clip 64 bolted to a part of the reed frame or lay 32, which, during the process of weav-

ing, is constantly reciprocated, beating the weft threads last entered by the shuttle and moving the webs towards the front, at which time it is most desirable to draw the knife 40 against the pile yarns.

5 The amount of movement that is imparted to the lever may be regulated by the position of the collars 61—61', and the position of the bolt 60 controls the movement transmitted to the knife.

10 Obviously upon swinging the rod 62 upward on the hinge 63 the motion of the knife ceases, permitting inspection and adjustment as may be required.

15 The foregoing disclosure is to be regarded as descriptive and illustrative only, and not as restrictive or limitative of the invention, of which obviously an embodiment may be constructed including many modifications

20 without departing from the general scope herein indicated and denoted in the appended claims.

25 Having thus described the invention, what is claimed as new and desired to secure by Letters Patent, is:—

30 1. In a loom for weaving a double web pile fabric, a knife disposed over the breast-beam of the loom to enter between the webs of the fabric for severing the pile, means for guiding, guarding and supporting said knife, means for maintaining the knife under tension, means actuated by the lay of the loom to transmit reciprocal motion to said knife, and means to adjust the movement of 35 the knife in timed relation to the strokes of said lay.

35 2. In a loom for weaving a double web pile fabric, a rail fixed on the breast-beam of the loom, said rail having a longitudinal slot in its rear edge, a knife blade slidable in the slot, guards extending beyond the knife on both 40 sides of the knife, said rail and knife entering between the webs of the fabric to sever the pile, pairs of guide pulleys fixed on the loom breast-beam, a flexible strap trained over said pulleys and engaging the ends of 45 said knife, a lever adjustably connected to said strap, means for stressing the strap, and means for adjustably actuating said lever operated by the lay of said loom.

50 In testimony whereof I affix my signature.
THEO. J. BACHOFEN.
